UNITED STATES PATENT OFFICE.

JOHN C. REED, OF ALLEGHENY, PENNSYLVANIA.

MOLDING APPARATUS.

SPECIFICATION forming part of Letters Patent No. 670,641, dated March 26, 1901.

Application filed March 22, 1900. Serial No. 9,794. (No model.)

To all whom it may concern:

Be it known that I, JOHN C. REED, a citizen of the United States, residing at Allegheny, in the county of Allegheny and State of Pennsylvania, have invented certain new and useful Improvements in Molding Apparatus; and I do hereby declare the following to be a full, clear, and exact description of the invention, such as will enable others skilled in the art to 5 to which it appertains to make and use the same.

My invention has relation to molding apparatus, and has for its object the provision of means for effecting the separation of the molded sand from the pattern without danger 15 of marring the mold by the separation of any of the sand from the mass of the same when the molded sand and the pattern are separated.

My invention consists in the novel construction, combination, and arrangement of parts hereinafter described and claimed.

My invention is particularly adapted for use in connection with apparatus for casting large and comparatively light hollow articles, 25 such as bath-tubs, and in which the cheek and cope or concave part of the mold is formed by packing and ramming sand into a flask and over a pattern or form which is sustained on a stationary base and in which the drag or 30 nowel part is formed by packing and ramming sand into a hollow pattern fixed in a suitable casing.

In the accompanying drawings, Figure 1 is a vertical longitudinal sectional view of the apparatus for forming the cheek and cope or concave part of a mold for bath-tubs on the line X X of Fig. 2. Fig. 2 is a plan view of the same with the pattern or form removed. Fig. 3 is an enlarged sectional detail of part 40 of the apparatus, and Fig. 4 is a vertical transverse sectional view of the apparatus, for forming the nowel or drag part of the mold. Fig. 5 is a plan view, enlarged, of a part of the mechanism shown in Fig. 4.

A designates the main base of the apparatus shown in Figs. 1 and 2, which consists of a casting substantially rectangular in shape and formed with a depression B, corresponding to the exterior contour of the article to 45 be cast. A frame C fits within said depression, resting upon a ledge a. The sides of the depression B are cut away, as shown at

b, to permit of a slight lateral and longitudinal movement of the frame C upon the ledge a.

D designates the pattern, which corresponds on its exterior surface to the exterior surface of the casting which is to be formed in the mold, which in this instance is a bathtub having a rounded rim. The pattern D is 55 securely attached to the frame C, and the latter is set at such depth in the base A that the curve of the rim of the pattern extends up to or slightly above the upper surface of the base A, so that the upper surface d of the 60 base corresponds to the position of the parting of the mold. The base A has holes a² a² at the corners of its horizontal flange for the insertion of pins or bolts to secure it to the flask N, having corresponding holes in its 65 flanged portion. The frame C has longitudinal and lateral cross-bars E E, which may be either cast integral with or secured to the frame, and at each side and at each end of the frame are projecting bars H H, that are 70 either cast integral with the frame or are securely attached to the same. In the drawings the bars H H are shown as separate pieces attached to the frame C by bolts h' h'. The bars H H pass through holes i i in the sides 75 and ends of the base A and register with ledges or projections K K on the sides and ends of the base. Holes k k are formed in the ledges K K, and holes h h are formed in the bars H H, the holes in the bars and the 80 holes in the ledges being exactly opposite to each other. The holes in the bars H H are countersunk from each side, so as to leave a contracted zone in each, and they are intended to receive a bar M, that fits loosely in the 85 central zone in the holes h h. The holes in the ledges K K are tapering or contracted toward their lower ends and are formed each with an internal flange h', which forms a stop for the lower end of the bar or lever M. The 90 bar M is intended to impart a vibratory movement to the frame C and through it to the pattern, and when the bar is drawn in any direction it will by reason of its great leverage 95 exert a powerful effect on the frame C.

N designates the flask, which is attached to the base A in the usual manner, and O designates the sand, which is packed into the flask and rammed around and over the pattern D.

Operation: The base A being placed in the desired position on the working floor, the flask N is lowered over the pattern and filled with sand, which is packed and rammed in the usual manner. When the flask has been filled and rammed, the bar M is inserted in the registering holes in one of the bars H and one of the ledges K, and the upper end of the bar is either moved to and fro positively and 10 a slight vibratory motion thereby communicated to the frame and to the pattern D or said bar M may be drawn or forced against one side of the hole in the bar H until a tension is produced. When the bar M is then 15 released from such strain or tension, the recoil will set up a vibration, which will expend itself in vibrating the frame C and pattern D, with an effect similar to that produced by rapidly-repeated blows of a hammer upon a 20 projecting portion of the frame C.

While I have described my invention as applied to the cheek and cope or concave part of the mold, it may be applied to the nowel or drag part, as illustrated in Fig. 4. In such 25 case the bars H H project from the flange of the casing P, which contains the concave pattern g and register with projections from the base of the nowel or drag S. In other respects the construction and operation of the 30 devices are substantially the same as already described with reference to the cheek and cope part of the mold.

Having described my invention, I claim—

1. In a molding apparatus, the combination with a pattern of a horizontally-movable frame to which said pattern is securely and firmly attached and a base upon which said frame is supported, the said frame and base being formed or provided with registering 35 projections having vertically-coinciding holes for the insertion of a bar or lever to vibrate or reciprocate said frame and produce a vibration of the pattern to free the latter from the sand of the mold.
2. In a molding apparatus, the combination with a base having slots or openings in its walls and ledges projecting outwardly below said openings, of projections in its base outside said openings and formed with ver- 40

tical holes, a horizontally-movable frame supported on said base and provided with arms or projections which extend through said slots or openings, register with the projections on the base and are formed with corresponding or coinciding holes, and a pattern 50 securely and firmly attached to said frame, the parts being so constructed and arranged as to permit of the insertion of a lever or bar in said coinciding holes to vibrate the frame and communicate such vibration to the pattern to free the latter from the sand in the mold.

3. In a molding apparatus, comprising a flask, a base upon which the flask rests and a pattern, the combination with a base having openings in its walls and ledges or projections outside said walls with vertical holes countersunk on both sides, of a horizontally-movable frame supported in said base and having arms or projections which extend 55 through the openings in the base and register with the projections thereof, and which are formed with countersunk holes which coincide with the holes in the projections of the base and a pattern which is securely and firmly attached to said frame, the parts being so constructed and combined that the frame and pattern may be vibrated by the movement and leverage of a bar or lever inserted in the coinciding holes, to free the pattern 60 from the sand in the mold.

4. In a molding apparatus, the combination with a pattern of a vibratable part to which said pattern is securely and firmly attached and a base upon which said vibratable 65 part is supported, the said vibratable part and base being formed or provided with registering projections having vertically-coinciding holes for the reception of a bar or lever to vibrate or reciprocate said vibratable part 70 and produce a vibration of the pattern to free the latter from the sand of the mold.

In testimony whereof I affix my signature in presence of two witnesses.

JOHN C. REED.
